(57) **CLAIM**

The ornamental design for a calibrated coffee glass, as shown and described.

DESCRIPTION

FIG. 1 is a perspective view of a calibrated coffee glass, showing our new design;

FIG. 2 is a front elevational view thereof, reverse text and calibration lines that is visible proximate the rear side of the calibrated coffee glass omitted for clarity of illustration;

FIG. 3 is a rear elevational view thereof, reverse text and calibration lines that is visible proximate the front side of the calibrated coffee glass omitted for clarity of illustration;

FIG. 4 is a left-side elevational view thereof, reverse text and calibration lines that is visible proximate the right side of the calibrated coffee glass omitted for clarity of illustration;

FIG. 5 is a right-side elevational view thereof, reverse text and calibration lines that is visible proximate the left side of the calibrated coffee glass omitted for clarity of illustration;

FIG. 6 is a top plan view thereof;

FIG. 7 is a bottom plan view thereof; and,

FIG. 8 is a cross-sectional view thereof, taken along line 8-8 of FIG. 6.

The broken lines depict portions of the calibrated coffee glass that form no part of the design.
